UNITED STATES PATENT OFFICE

EDWARD J. O'NEILL, OF BRIDGEPORT, CONNECTICUT

BED

Application filed November 16, 1929. Serial No. 407,731.

This invention relates to new and useful improvements in hospital or invalid beds, and has for an object the provision of a bed including means whereby the bed sheets may be readily and quickly changed without moving or otherwise disturbing the occupant of the bed. 55

More specifically the invention provides an invalid or hospital bed including means 10 positioned beneath the bed in combination with a pair of mattresses, the parts being so arranged that one mattress with its sheet may be rolled from under the patient as the second mattress and its sheet are moved into 15 position under the patient.

Other objects and advantages will become apparent from a consideration of the following detailed description taken in connection with the accompanying drawing wherein one 20 satisfactory embodiment of the invention is shown. However it is to be understood that the description and drawing are for the purpose of making clear the construction and operation of the principles of the invention 25 and are not to be considered a limiting of its scope since changes in construction, combination and arrangement of parts may well be made within the scope of the appended claims to which reference must be had for a 30 definition of the limitations of the invention. 70

In the drawing:

Fig. 1 is a side elevational view of the improved bed, part of the head and foot being omitted to facilitate illustration of detail; 35 Fig. 2 is a view of one end section, substantially on the line 2—2 of Fig. 1; 75

Fig. 3 is a plan view of a portion of the bed; and 80 Fig. 4 shows a detached side view of one 40 of the links 35 with attached hooks.

Referring in detail to the drawings, the bed includes a head and a foot 5 and 6 respectively, each comprising legs or uprights 7 and 8 connected by cross pieces 9 and 10. Extending between the head 5 and foot 6, at each side of the bed are the side rails 11, preferably somewhat L shaped as shown in Fig. 2. 85

Disposed beneath the bed, at the head and foot thereof, are pairs of standards 12 and 13 90 at their upper ends providing bearings for 95

rollers 14 and 15. These rollers are disposed on shafts 16 and 17 respectively, and on the shafts at the ends of the rollers are discs or plates 18, the discs and rollers forming spools. Straps or other means 19 are used for securing the standards 12 and 13 to the legs or uprights 7 and 8, and if necessary they may also be further fastened by securing them to the floor. 55

Mattresses 20 and 21 are used with the bed, and sheets 22 and 23 are associated with the mattresses. As clearly shown the sheet 22 is buttoned to mattress 20 at 24 and a portion of the mattress and its associated sheet is wound about the roller 14. The end of the mattress 20, remote from the buttons 24, is secured to a rope or cable 25 as at 26 and the cable is secured to the roller. A crank 27 is shiftable from shaft 16 to shaft 17 in order that either roller 14 or 15 may be wound. 60 65

The mattress 21 and sheet 23 are shown as occupying the most of the bed. Sheet 23 is buttoned to mattress 21 as at 28 and 29. Also one end of mattress 21 is connected to a rope or cable 30 as at 31, and the other end of cable 30 is secured to roller 15. As is clear from the drawing, mattresses 20 and 21 are doubled on themselves about rollers 32 and 33. The ends of the rollers rest in the L shaped side rails 11 and have extensions 34 70 75 connected at each side of the mattresses by links 35. 80

The links 35 hold the rollers 32 and 33 in definite spaced relation, there being space between the rollers to accommodate the two mattresses and sheets with but little space to spare. Also, see Fig. 2, it is to be noted that the links and rollers receive the side rails 11 between them. A roller 36 of soft rubber or the like is disposed on the mattresses and occupies the space between them. 85 90

In the operation of the device, assuming that the mattress 21 and sheet 23 are in place and it is desired to change, the crank 27 is applied to shaft 17 and the shaft rotated to wind the mattress on to roller 15 after sheet 23 is unbuttoned at 29. Preparatory to winding the mattress 21 onto roller 15 sheet 23 will be unbuttoned as at 29 whereupon said 100

sheet will fall to the floor and by unbuttoning it at 28 it can be removed.

During the time the foregoing operation is taking place, owing to the links connecting 5 rollers 32 and 33, mattress 20 and sheet 22 are moved or rolled into place. Roller 36 prevents the patient from being caught and pinched between the mattresses.

In this connection it will first be necessary 10 to secure the links 35 to one end of the bedstead so that the rolls 32 and 33 will be held in position during and after the removal of the mattress. I have therefore mounted a pair of oppositely extended hooks 37 upon 15 each of the links 35, each hook adapted to engage a pin 38 upon a bed post, two of said hooks, one of each pair, serving to secure the link and the rolls carried thereby to the forward bed posts and the remaining two hooks 20 to secure it to the other two posts.

It will thus be seen that the bed can be made up with one mattress, in which case but one end of the mattress, together with the sheet, would be secured to one end of the bed 25 while the other end portion of the mattress is carried over one of the rolls and held by the reel. In this case, the mattress would not be buttoned at the foot end of the bed, where the mattress passes over the roll. In this respect, it will also be understood that the rolls 30 in question are carried upon the bedstead and held through links and hooks to the posts at the end.

Now when it is again desired to change the sheet one end of a clean sheet is secured by buttons 28, and sheet 22 is unbuttoned from mattress 20 and the mattress wound onto roller 14. The clean sheet is moved into place beneath the occupant of the bed on mattress 40 21 as the latter is moved or rolled into place beneath the patient.

Having thus described the invention, what I claim is:

1. In combination, a bed, a pair of mattresses, means beneath the bed onto which the mattresses may be wound, and means whereby as one of the mattresses is moved from the bed the other is moved into place on the bed.

2. In combination, a bed, a pair of mattresses, means for securing a sheet to each of said mattresses, a pair of rollers, said mattresses doubled upon themselves about said rollers, means connecting said rollers whereby they move together, means beneath the bed onto which the mattresses may be wound, and means for operating said last means, said rollers cooperating whereby as one of said mattresses is wound onto said means the rollers are moved and draw the other mattress 55 into place on the bed.

3. The combination as in claim 2, said bed having side rails and the rollers and connecting means engaging said side rails and being guided thereby.

4. The combination as in claim 2, including

a roller disposed on top of the mattresses in a position between the rollers about which the mattresses are doubled.

5. In a bed, the combination of a bedstead, a pair of mattresses, one end of one of which is detachably connected to one end of the bedstead and an end of the other mattress being attached to the other end of the bedstead, rolls carried by the bedstead over which said mattresses are carried, separate means beneath the bedstead upon which each of the mattresses are wound, and means for retaining the rolls adjacent either end of the bedstead while the mattresses are attached or removed.

6. In a bed, the combination of a bedstead, a pair of rolls mounted to travel thereon, links connecting the ends of the rolls, a mattress carried by each roll, one end of each of said mattresses being detachably connected to one end of the bedstead, means for drawing the mattresses over the rolls to shift the position of the mattresses, and pivoted means on the links for connecting the links to the bedstead to permit the attachment or removal of a mattress.

Signed at Bridgeport in the county of Fairfield and State of Connecticut this first day of November A. D. 1929.

EDWARD J. O'NEILL.
